UNITED STATES PATENT OFFICE.

JOHN WM. FORSMAN, OF DEEP RIVER, WASHINGTON.

WATCHCASE.

1,135,573.

Specification of Letters Patent. Patented Apr. 13, 1915.

Application filed August 17, 1911. Serial No. 644,592.

To all whom it may concern:

Be it known that I, JOHN WILLIAM FORSMAN, a citizen of the United States, residing at Deep River, in the county of Wahkiakum, 5 State of Washington, have invented certain new and useful Improvements in Watchcases; and I do hereby declare the following to be a full, clear, and exact description of the invention, such as will enable others 10 skilled in the art to which it appertains to make and use the same.

This invention relates to new and useful improvements in watch cases.

The object of this invention is the provision 15 of a watch case so constructed that moisture will be prevented from entering therein to engage the works.

A further object of this invention is to improve and simplify devices of this character 20 rendering them comparatively simple and inexpensive to manufacture, reliable and efficient in use and readily operated.

With the above and other objects in view this invention resides in the novel features 25 of construction, formations, combinations and arrangements of parts to be hereinafter more fully described, claimed and illustrated in the accompanying drawing, in which:—

30 Figure 1 is a front elevation of my invention. Fig. 2 is a longitudinal sectional view taken on the line 2—2 of Fig. 1. Fig. 3 is a detailed perspective view of the bearing collar removed, and Fig. 4 is a detailed 35 perspective view of the cap removed.

Referring to the drawing by similar characters of reference throughout the several views, the numeral 5 designates generally 40 my improved watch casing which consists of the customary outer casing 6 in which is located the usual works supporting ring 7, the upper face of which lies flush with the upper face of an inner peripheral flange 8 formed upon the watch casing and producing 45 a resultant shoulder at the outer periphery of the said watch casing. The exterior of the flange 8 is threaded as at 10 for engagement with the crystal ring 11, while the shoulder 9 is provided with an

annular groove 12 in which is located a 50 gasket 13 for engagement with the inner end of the crystal ring 11, by means of which the front of the watch casing is sealed against the admission of moisture.

The stem sleeve 14 is provided adjacent its 55 connection with the attaching ring 15 with an annular flange 16, the upper end of which is provided with a groove 18 in which is located a gasket 19 for contact with the lower end of a closing cap 20 which is 60 threaded upon the stem sleeve 14 whereby the said stem opening is sealed against the admission of moisture. In order to prevent any undesired entrance of moisture between the crystal and the ring 11 the exterior edges 65 of the said crystal are coated as indicated by the numeral 21 with rubber or other similar material, which when brought in contact with the retaining beads of the ring 11 securely seals the connection between the 70 crystal and its supporting ring.

From the foregoing disclosure taken in connection with the accompanying drawings, it will be manifest that a watch casing for the purposes specified is provided which 75 will answer all the necessary requirements of such a device.

Having thus fully described this invention, what I claim as new and desire to protect by Letters Patent, is:

The combination of a watch case having a tubular pendant provided with exterior threads at its outer end, a ring adjustable on said thread and provided with a circular groove on its outer end, a gasket in said 85 groove normally projecting beyond the outer face of the ring, and a cap adjustable on the threads of the stem whereby the adjustment of the ring and cap toward each other will engage the gasket with the cap while the 90 ring will serve as a lock nut.

In testimony whereof, I affix my signature, in presence of two witnesses.

JOHN WM. FORSMAN.

Witnesses:

CHAS. RINEL,
MATTE GOUSILA.
